CALENDAR CLOCK

Manuel P. Bell, Albuquerque, N. Mex.

Application October 16, 1952, Serial No. 315,039

4 Claims. (Cl. 58—6)

This invention relates to new and useful improvements in date displaying mechanisms and the primary object of the present invention is to provide a dating mechanism that is operatively connected to a clock so that the year, month, day of the month, and day of the week will be readily observable.

Another important object of the present invention is to provide a date mechanism including novel and improved means for automatically displaying the twenty-ninth day of February every four years.

Yet another object of the present invention is to provide a date mechanism including an endless tape having the days of the months thereon and a power driven member having a drop tooth for periodically engaging a drive roll for the tape until the 29th day of February is to be displayed.

A further object of the present invention is to provide a calendar clock that is extremely small and compact in structure and which involves a simple drive connection with the hand supporting shaft of a clock.

A still further aim of the present invention is to provide a date mechanism of the aforementioned character, that is extremely simple and practical in construction, strong and reliable in use, efficient and durable in operation, inexpensive to manufacture, and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a front elevational view of the present invention and with the front wall of the casing broken away for the convenience of explanation;

Figure 2 is a longitudinal vertical sectional view taken substantially on the plane of broken section line 2—2 of Figure 1;

Figure 3 is a horizontal sectional view taken through the upper portion of the invention shown in Figure 2;

Figure 4 is an enlarged fragmentary vertical sectional view taken substantially on the plane of section line 4—4 of Figure 1;

Figure 5 is an enlarged detailed fragmentary vertical sectional view taken substantially on the plane of section line 5—5 and showing the tooth element disposed within its accommodating recess;

Figure 6 is a view similar to Figure 5 but showing the tooth element projected radially outwardly of the supporting member therefor;

Figure 7 is a horizontal sectional view taken substantially on the plane of section line 7—7 of Figure 5;

Figure 8 is an enlarged fragmentary vertical sectional view taken substantially on the plane of section line 8—8 of Figure 1;

Figure 9 is a perspective view of one of the spider members used in the invention;

Figure 10 is a perspective view of the other spider member used in the invention; and

2

Figure 11 is a perspective view of the invention.

Referring now to the drawings in detail, wherein for the purpose of illustration, there is disclosed a preferred embodiment of the present invention, the numeral 10 represents a casing having forward and rear walls 12 and 14. Forward wall 12 is formed with a circular opening 16 in which there is mounted, by suitable means, an electric clock 18 of any well known structure. The forward wall 12 is also provided with a pair of side-by-side slots 20 and 22 and an upper slot 24. Transparent strips 26 are suitably held in the slots 20, 22, 24. The rear wall 14 is provided with an opening 28 in which there is positioned a removable closure or door 30 having latch means 32 for retaining the same in its closed position.

A vertical supporting wall 34 is fixed within the casing, preferably to the upper and lower walls of the casing and supports upper and lower groups of horizontally disposed guide rollers or spools 36 and 38. An endless indicia bearing strip or tape 40 is trained back and forth between the rollers 36 and 38 and extends over the upper rollers 36 and under the lower rollers 38 as shown in Figure 2. Additional guide rollers 42, 44, 46 and 48 are also supported on wall 34 and have the tape trained thereabout. These latest rollers, 42, 44, 46 and 48 are so arranged as to remove slack in the tape.

The upper wall of casing 10 supports an ordinary four wheel counter mechanism 50 that registers with slot 24. The mechanism 50 includes an operating shaft 52 on which there is fixed a ratchet 54 that is adapted to be engaged by a lug or dog 56 on a side edge of the tape 40 as the latter is moved. The tape 40 has all months and days of the months thereon including February 29, and the lug 56 is so disposed that it will engage a tooth 35 of the ratchet 54 as the indicia "January 1" approaches the slot 22 to change the year indicated by counter mechanism 50.

A bracket 58 is secured to and depends from the upper wall of casing 10 and rotatably supports a horizontally disposed tubular shaft or spindle 60 which forms the driving shaft for the tape 40. A rod 62 extends axially through the shaft 60 and its ends project outwardly from the ends of the shaft 60 and support a wheel 64 and a sprocket 66. Wheel 64 has the days of the week thereon that will sequentially register with the slot 20 as the rod 62 is rotated. The shaft 60 has a sprocket 66 fixed thereto and the sprocket 63 is spaced from and disposed alongside of the sprocket 66. The sprockets 66 and 68 are similar in size and have an equal number of circumferentially spaced teeth thereon.

A support bracket 70 is fixed to a side wall of casing 10 and rotatably supports a vertical shaft 72 having upper and lower bevelled gears 74 and 76 fixedly secured to its ends. The bevelled gear 76 meshes with a similar bevelled gear 78 at one end of a horizontal shaft 80. The shaft 80 is rotatably supported by the casing of clock 18 and its inner end carries a bevel gear 82 that meshes with a bevel gear 84 fixed to the hand supporting shaft 86 of the clock 18, whereby the motor 60 operating the clock mechanism will also cause the shafts 80 and 72 to be rotated for a purpose now to be described.

A horizontal shaft 88 is rotatably supported in bearings carried by the bracket 70. One end of shaft 80 fixedly supports a bevel gear 90 that meshes with gears 74 whereas the other end of shaft 88 fixedly supports an actuating member or cylinder 92 having a peripheral tooth 94 (Figure 4) for engaging the sprockets 66, 68 to rotate both shafts 60 and rod 62.

Member 92 is formed with a peripheral recess or slot 96 having an end wall 98. A movable tooth element 100 is slidable in the recess 96 radially of the member

92 and carries a headed lug 102 at one end whose shank is slidably received in a guide slot 104 formed in end wall 98. A coil spring 106 terminally secured to lug 102 and member 92 yieldingly urges the tooth element 100 radially inwardly of member 92 and within recess 96.

Means is provided for moving the tooth element 100 radially outwardly of the recess 96 and this means comprises a sliding wedge 108 whose sloping face engages the slanting face 110 of tooth element 100. Recess 96 is formed with a shoulder 112 for engaging the notch 114 of wedge 108 to limit movement of the wedge away from the tooth element. An arm 116 is slidably and pivotally attached, as 118, to the sliding wedge 108, as shown in Figure 7, and is adapted to engage a stop or abutment 120 on bracket 70.

When tooth element 100 is urged radially outwardly from the recess 96 by the wedge 108, as shown in Figure 6, the tooth element 100 will engage between two teeth 6, the tooth element 100 of ratchet 68 to permit rotation of the member 92 and shaft 60 as a unit until the tooth element 100 clears ratchet 68.

Means is provided for engaging the arm 116 to move the wedge forcefully against the tooth element in order to urge the latter to its position shown in Figure 6. This means consists of a plate element 122 that is fixed to the bracket 70 and which supports a horizontal pin 124 for a swingable arm 126. A ring element 128a is fixed to the lower end of arm 126 and a contact shoe or tooth 128 is fixed to the upper end of arm 126.

A hanger bracket 130 secured to the upper wall of casing 10 rotatably supports a horizontal rod 132 having member spider members 134 and 136 fixed to its ends. Member 134 is composed of four radially disposed arms, whereas member 136 is composed of but three radially disposed arms whose relative positions are shown in Figures 8 and 9. A spring urged locking pawl 138, pivoted to bracket 130, will sequentially engage the arms of member 134 to prevent back rotation of rod 132 and hence the members 134 and 136.

Rod 132 is disposed perpendicular to the vertical flight of tape 40 that registers with the slot 22 and portion of tape 40 that registers with the slot 22 and member 134 is disposed relatively close to a side edge of tape 40 to be engaged by a lug or dog 140 that is secured to this side edge as the tape is moved. Lug 140 is disposed adjacent the "February 26" indicia on tape 40 so that the "February 28" indicia approaches slot 22, lug 140 will engage one arm of the member 134 to rotate members 134 and 136 ninety degrees. As this step is being accomplished, one arm of member 136 will engage tooth 128 to swing arm 126 and cause ring element 128a to engage arm 116 and move the wedge against the tooth element 100 and the latter radially outwardly of member 92. Arm 116 continues to ride against element 128 as the member 92 is rotated until the arm 116 engages the stop 120 whereupon the arm 116 will be pivoted out of engagement with the ring element 128a, thus permitting the wedge 108 to be pulled away from the tooth element 100 by action of the spring 106. Tooth element 100 when disposed radially outwardly of the member 92, as shown in Figure 6, will engage the sprocket 68 to move the tape 40 an additional step which causes "February 29" to pass over the slot 22.

The above procedure is repeated for three successive years since the member 136 is provided with three arms. However, the fourth year (leap year) as the fourth arm of member 134 is engaged by lug 140, member 136 is rotated without engaging the tooth 128 of arm 126, and hence tooth element 100 is retracted and will not engage sprocket 68 so that "February 29" will register with the slot 22.

It will be noted that the tooth 94 will engage both the sprockets 66 and 68 to rotate the tape one step and the wheel 64 one step. However, an additional step of movement for tape 40 is accomplished by tooth ele-

ment 100 engaging the sprocket 68, this latter step being accomplished for three successive years, by the actuation of the tooth element 100 in the following manner:

The lug 140 upon movement of the tape 40 will contact the arms of member 134. This will cause rotation of the rod 132 on which the member 134 as well as the member 136 are rigidly affixed, and rotation of the rod 132 will, for three of each four years, cause an arm of member 136 to actuate the ring member 128a and press it against the arm 116 holding the arm 116 and hence the tooth element 100 in engagement with the sprocket 68 to give the sprocket 68 an extra turn. The arm 116 is freed from engagement with the ring member 128a by contact with the stop 120 which causes the arm 116 to pivot outside of the diameter of the ring member 128a.

Having described the invention, what is claimed as new is:

1. A calendar clock comprising a casing having a front wall with openings therein, a clock supported in one of the openings and including a driven hand-supporting shaft, an endless date bearing strip within the casing, guide rollers in the casing over which the strip is trained, the dates on said strip adapted to sequentially register with an opening in the front wall, a drive roller over which said strip is trained, said drive roller being tubular, a rod extending through and journaled in said drive roller, a day indicating roller fixed on the rod and registering with an opening in said front wall, a first sprocket fixed on said driven roller, a second sprocket fixed on said rod, a driven member operatively connected to said shaft for rotation therewith and having a tooth for engaging the sprockets to rotate the driven spool and the rod, a second tooth carried by the member and engageable with the sprocket on said driven roller and movable radially outwardly from and inwardly of the periphery of said member, means for engaging and urging the second tooth radially outwardly from the member, means engageable with the second tooth urging means permitting retraction of the latter, and means on the strip for engaging the second tooth urging means to move the latter to a position for forcing the second tooth radially outwardly from the member.

2. A calendar clock comprising a casing having a front wall with openings therein, a clock supported in one of the openings and including a driven hand-supporting shaft, an endless date bearing strip within the casing, guide rollers in the casing over which the strip is trained, the dates on said strip adapted to sequentially register with an opening in the front wall, a drive roller over which said strip is trained, said drive roller being tubular, a rod extending through and journaled in said drive roller, a day indicating roller fixed on the rod and registering with an opening in said front wall, a first sprocket fixed on said driven roller, a second sprocket fixed on said rod, a driven member operatively connected to said shaft for rotation therewith and having a tooth for engaging the sprockets to rotate the driven spool and the rod, a second tooth carried by the member and engageable with the sprocket on said driven roller and movable radially outwardly from and inwardly of the periphery of said member, a sliding wedge carried by the member and engageable with the second tooth to urge the latter radially outwardly from the member, means engageable with the wedge to permit retraction of the same, and actuating means on the strip for periodically causing actuation of the wedge to move the same to a position for urging the second tooth radially outwardly from the member.

3. A calendar clock comprising a casing having a front wall with openings therein, a clock supported in one of the openings and including a driven hand-supporting shaft, an endless date bearing strip within the casing, guide rollers in the casing over which the strip is trained, the dates on said strip adapted to sequentially register with an opening in the front wall, a drive roller over which said strip is trained, said drive roller being tubular, a rod extending

through and journaled in said drive roller, a day indicating roller fixed on the rod and registering with an opening in said front wall, a first sprocket fixed on said driven roller, a second sprocket fixed on said rod, a driven member operatively connected to said shaft for rotation therewith and having a tooth for engaging the sprockets to rotate the driven spool and the rod, a second tooth carried by the member and engageable with the sprocket on said driven roller and movable radially outwardly from and inwardly of the periphery of said member, a sliding 10 wedge carried by the member and engageable with the second tooth to urge the latter radially outwardly from the member, means engageable with the wedge to permit retraction of the same, and actuating means on the strip for periodically causing actuation of the wedge to move the same to a position for urging the second tooth radially outwardly from the member, and a coil spring terminally attached to said second tooth and said member yieldingly urging the second tooth radially inwardly of said member.

4. A calendar clock comprising a casing having a front wall with openings therein, a clock supported in one of the openings and including a driven hand-supporting shaft, an endless date bearing strip within the casing, guide rollers in the casing over which the strip is trained, the dates on said strip adapted to sequentially register with an opening in the front wall, a drive roller over which said strip is trained, said drive roller being tubular, a rod extending through and journaled in said drive roller, a day indicat- 25

ing roller fixed on the rod and registering with an opening in said front wall, a first sprocket fixed on said driven roller, a second sprocket fixed on said rod, a driven member operatively connected to said shaft for rotation therewith and having a tooth for engaging the sprockets to rotate the driven spool and the rod, a second tooth carried by the member and engageable with the sprocket on said driven roller and movable radially outwardly from and inwardly of the periphery of said member, a sliding 10 wedge carried by the member and engageable with the second tooth to urge the latter radially outwardly from the member, means engageable with the wedge to permit retraction of the same, and actuating means on the strip for periodically causing actuation of the wedge to move the same to a position for urging the second tooth radially outwardly from the member, and an arm pivotally and slidably secured to said wedge and forming an abutment for said actuating means.
